RACKET STRING TIGHTENING MACHINE

Joseph Saladino, Reading, Mass.

Application September 4, 1934, Serial No. 742,598

10 Claims. (Cl. 273—73)

This invention relates to a racket string tightening machine, and to improvements to the machine covered by my patent application Serial No. 737,562, filing date July 30, 1934.

5 One object of my invention is to provide means whereby my machine may be set to permit pulling a racket string to a certain degree of tightness and no further. This will save the operator the necessity of watching the gauge each time a 10 string is pulled, as my invention will not permit tightening of the string beyond a certain point, and by operating the mechanism to that point each time every string will be tightened equally.

Another object is to improve upon the means 15 for holding the racket so that the fastening of the racket in place and then releasing it may be done more readily. Another object is to make said holding means readily adjustable to various sizes of rackets without the necessity of using 20 additional parts for the smaller rackets. Another object is to make said holding means simple in construction, and so shaped that the parts will not mar the finish of the racket while it is being held.

25 The foregoing and other objects which will appear as the nature of the invention is better understood, may be accomplished by a construction, combination and operative arrangement of parts such as is disclosed by the drawings. The 30 nature of the invention is such as to render it susceptible to various changes and modifications, and, therefore, I am not to be limited to the construction disclosed by the drawings; but am entitled to all such changes therefrom as fall 35 within the scope of my claims.

In the drawings:

Figure 1 is a side elevation view of my racket stringing machine.

Figure 2 is a perspective view of the front and 40 side clamps used to hold the racket during the stringing operation.

Figure 3 is a plan view of my machine.

Figure 4 is an enlarged sectional view taken on the line 4—4 of Figure 3, showing the rear clamp 45 for holding the racket, the broken lines indicating the racket.

Figure 5 is an enlarged sectional view taken on the line 5—5 of Figure 1, showing the rear clamp and its dovetailed sliding portion.

50 Figure 6 is an enlarged sectional view taken on the line 6—6 of Figure 1 showing a front and side clamp.

Figure 7 is a sectional view taken on the line 55 7—7 of Figure 3 showing the parts of the string tightening device in detail.

As illustrated, my machine has a supporting stand or base 15 having a bossed portion 16 into which a vertical standard 17 fits. Attached to said standard by screws 19 is a guide bracket 18, and extending between said bracket 18 and said standard 17 is a treadle 21 pivoted as at 22 to a yoke 23 which screws into said base 15 as at 24. Pressure on said treadle 21 by the foot of the operator actuates the string tightening device later described. An eye member 30 fits in 10 said treadle 21 to receive a cable or belt 31 which passes over a pulley later described, and is fastened at the other end to a spring 32 which in turn is fastened to said bracket 18.

Said standard 17 telescopically engages a vertical sleeve 34, and is held in any desired position by a hand screw 33, so that the height of my machine may be adjusted vertically to the convenience of the operator. Mounted on said sleeve 34 is a tool support or table 35 having a projecting lug 36 in which is a hole 37, referred to later. A bracket 38 is fastened to said sleeve 34 by a set screw 39, and said bracket 38 has an arm or upstanding part 40 which supports the string tightening device later described.

A holder 42 supports and holds the racket 50 to be strung, and is rotatable so that the position of said racket may be changed as the stringing proceeds. Said holder 42 has a supporting frame 43 which is rotatably mounted on said bracket 38. A cap or plate 45 rests on said frame 43 and is held to said bracket 38 by a screw 46. Said holder 42 has a top 48 having downwardly projecting lugs 49 on opposite sides integral with said frame 43, on which top 48 the tennis or 30 other playing racket 50 is supported while being strung. The ordinary racket consists of a curved portion known as the bow head, which receives the stringing, and a straight handle which extends from said bow head. In stringing a racket the operator, stands in front of the string tightening device.

Said holder has a rear clamp 52 which is adjustable horizontally and vertically, which holds the bow head of the racket 50 from any horizontal or upward movement. Said clamp 52 consists of a sliding portion 53 having a dovetail portion 54 which slidably fits in a dovetail slot 55 made in the top 48 of said holder 42, and extending from the top surface downwardly, 50 thereby permitting sufficient horizontal movement of said sliding portion 54 to engage the bow head of rackets of various sizes. A screw 56 extends horizontally through said sliding portion 53 and is screwed into said holder frame 43. A 55

flange 57 is an integral part of said screw 56 and spaced therefrom is a wing grip 58 on said screw, the said sliding portion 53, being held between them, so that forward or reverse movement of 5 said sliding portion 53 may be obtained by turning said wing grip 58. A pin 59 holds said wing nut 58 to said screw 56. An arm 60 projects upwardly from said dovetail portion 54 terminating in a finger portion 61. Said arm comes into 10 contact with the racket 50 when moved into holding position, the curvature 62 of the outer surface of said arm 60 corresponding with the curvature of the racket. Said finger portion 61 is made narrower than the rest of said arm 60 so 15 as to avoid having it block string holes in said racket 50.

Said rear clamp 52 has a top retaining plate 63 which rests on the top of said racket 50 when moved to holding position, thereby preventing 20 any upward movement of the racket. A screw 64 passes through said retaining plate 63, having a wing nut 65 at one end, the screwing down of which makes it bear against said plate 63. A head 66 at the other end of said screw 64 serves as 25 a guide member as said screw is slid horizontally in an inverted T-slot 67 made in said sliding portion 53 of said clamp 52. This retaining plate 63 is not absolutely necessary, as ordinarily the clamps are sufficient to hold the racket, but can 30 be availed of should the racket move upwardly during stringing. Except for this retaining plate, the rear clamp is the same as the front and side clamps later described.

A front clamp 70 slides in a dovetail slot 71 made 35 in said holder top 48, and is the same as the rear clamp 52, except there is no provision for said retaining plate 63.

Said holder 42 also has a pair of said clamps 73 which are the same as said front clamp 70, sliding 40 in dovetail slots 74 made in said holder top 48 the same as are the said slots 55 and 71 for the rear and front clamps respectively.

The strings in the racket are pulled tight by a rotatable tensioning or tightening device 84 which has a pulley 85 fastened thereto by 45 screws 86 which extend from a ratchet 87 into said pulley. Said pulley 85 has a hole 82 transverse to the axis thereof extending therethrough through which said cable 31 extends and in which it is held. Said device 84 has a ratchet 87, a portion of which has teeth 88. A screw 89 extends through a portion of said ratchet 87 into a horizontal shaft 90 which has a cap 91 at one end. A helical spring 92 has one end as at 93 projecting into said cap 91 as illustrated in Figure 7 of the drawings, the other end 50 94 passing into a hole in the wall of a barrel 96, which together with said cap 91 encloses said spring 92. A bushing 97 which surrounds a portion of said shaft 90, is made integral with said barrel 96 and rotatably fits into a housing 98 which is an integral extension of said bracket arm 40. An indicator pointer 99 is fastened to 55 said bracket arm 40 to show how tight the stringing has been pulled, said pointer being opposite a scale 100 marked on the outside of said barrel 96, so that rotation of said barrel brings different numbers on said scale opposite said pointer to thereby show to what degree the strings in 60 the racket have been tightened.

A cleat 101 on said barrel 96 projects slightly above it, being held by screws 102. The string to be tightened is wound around said cleat 101 to firmly hold it, so that rotation of said tightening 65 device 84 pulls the string tight, and when the

indicator mark 99 indicates on the scale 100 that the string has been tightened to the degree desired, the string is then held there by inserting an awl or other pointed instrument in the racket hole through which the string passes. 5

As will be seen, when the treadle or lever 21 is depressed said pulley 85 is rotated, thereby tightening the string in the racket, as the rotation of said pulley rotates said shaft 90 which in turn acts upon said spring 92 to rotate said barrel 96 10 with the scale 100 marked thereon.

To make certain that every string in the racket will be tightened to the same degree, and to save the operator the trouble of continually watching the indicator pointer and scale, I provide means 15 to automatically limit the downward movement of said lever or treadle 21, which consist of an adjusting rod 105 having a knurled knob 106 by which it is turned. Said adjusting rod 105 loosely passes through said hole 31 in said tool table 20 lug 36, and is connected to an adjusting screw 107 by means of a universal joint member 108 of well known construction. Said adjusting screw threads, as at 109, into said treadle or lever 21 and may project beyond it. When it is desired to 25 limit the downward movement of said treadle or lever said adjusting screw is screwed downwardly, with the result that it will strike said base 15 and stop the said downward movement. Once the operator determines how tight the 30 strings in a racket are to be pulled, said adjusting screw is turned to permit depression of said treadle to that point, and each string is tightened to the same degree by merely depressing said treadle as far as it will go. 35

What I claim is:

1. A holder for a racket string tightening machine comprising a frame embodying a top, said top having slotted passages therein, clamp members to hold a racket slidably mounted in said 40 passages, said clamp members embodying a downwardly projecting portion extending outside of said top having a hole therein, and screw means passing through said hole and screwing into said frame below said top. 45

2. A holder for a racket string tightening machine comprising a frame embodying a top, said top having slotted passages therein, clamp members to hold a racket slidably mounted in said 50 passages, said clamp members embodying a downwardly projecting portion extending outside of said top having a hole therein, and screw means extending from outside said downwardly projecting portion and passing through said hole and screwing into said frame below said top, said 55 screw means embodying a flange adjacent the inside surface of said downwardly projecting portion whereby reverse movement of said screw means will move said clamp members outwardly. 60

3. A holder for a racket string tightening machine comprising a top outer rim, said top rim having passages therein, clamp means to hold a racket slidably extending into said passages, and means to propel said clamp means to a selected 65 position.

4. A holder for a racket string tightening machine comprising a top outer rim, said top rim having passages extending all the way across it, clamp means to hold a racket slidably extending into said passages and embodying a body portion 70 extending beyond said passages and an upwardly extending member beyond the inner side of said top rim, and means to propel said clamp means to a selected position. 75

5. A holder for a racket string tightening ma-

chine comprising a frame embodying a top outer rim, said stop rim having passages therein, clamp means to hold a racket slidably extending into said passages, and means entering said frame 5 below said top rim to propel said clamp means to a selected position.

6. A holder for a racket string tightening machine comprising a top outer rim, said top rim having passages in its upper portion, clamp means 10 to hold a racket slidably extending into said passages and extending beyond the inner side of said top rim, and means to propel said clamp means to a selected position.

7. A holder for a racket string tightening machine comprising a frame embodying a top outer rim, said top rim having passages therein, clamp members to hold a racket slidably mounted in 15 said passages, and screw means in said clamp members and screwing into said frame below said 20 passages whereby said clamp members may be slidably moved in said passages crosswise of said top rim.

8. A holder for a racket string tightening machine, comprising a frame embodying a top outer 25 rim on which a racket is adapted to rest, said top rim having passages in the upper portion thereof, clamp means to hold a racket slidably

extending into said passages and embodying an upwardly extending member extending horizontally beyond the inner side of said top rim and said racket, and means to propel said clamp means to a selected position.

9. A holder for a racket string tightening machine comprising a frame embodying a top outer rim to support the racket, said top rim having 10 passages in its top and upper portion extending across it, clamp means to hold a racket slidably extending into said passages embodying a body portion which is level with said top rim and an arm beyond said passages extending upwardly from said body portion at one end thereof, and means to propel said clamp means to a selected 15 position.

10. A holder for a racket string tightening machine comprising a top rim having passages therein extending across said rim, the depth of 20 said passages being less than the depth of said rim whereby said rim provides a bottom for said passages, clamp means to hold a racket slidably extending into said passages and resting on said bottom, and means to hold said clamp means in 25 position.

JOSEPH SALADINO.
